UNITED STATES PATENT OFFICE.

FRANK C. FIX, OF LANCASTER, PENNSYLVANIA, ASSIGNOR TO ARMSTRONG CORK COMPANY, OF PITTSBURGH, PENNSYLVANIA, A CORPORATION OF PENNSYLVANIA.

METHOD AND APPARATUS FOR HEATING GEM DUCK.

1,402,484.

Specification of Letters Patent.

Patented Jan. 3, 1922.

Application filed September 26, 1919. Serial No. 326,657.

To all whom it may concern:

Be it known that I, FRANK C. FIX, a citizen of the United States, residing at Lancaster, in the county of Lancaster, Pennsylvania, have invented a new and useful Method and Apparatus for Heating Gem Duck, of which the following is a full, clear, and exact description, reference being had to the accompanying drawings, forming 10 part of this specification.

The present invention relates broadly to heating materials in strip or circular form having an adhesive coating applied thereto, and more particularly to a method and apparatus for heating gem duck.

The principal object of the present invention is to provide a compact apparatus by means of which gem duck may be preliminarily softened to facilitate subsequent 20 forming in on the inner sole, and then treated to soften the adhesive.

Another object of the invention is to maintain the duck after the adhesive has been softened in such state that it is ready 25 for use.

Still another object of the present invention is to provide an apparatus of the type referred to which may employ any one of several different types of heating systems 30 whereby the use of hot water in the water box is unnecessary.

The foregoing and other objects, together with their attendant advantages, will be apparent as the invention becomes better understood by reference to the accompanying specification and drawing forming a part thereof, it being premised that changes may be made in the various details and the manner of operation within the scope of the 35 appended claims without departing from the spirit of the invention.

Figure 1 is a side elevation partly in section of one form of a machine embodying my invention;

45 Figure 2 is a plan view of such machine; Figure 3 is a vertical section through the machine along the line III—III of Figure 1;

50 Figures 4 and 5 are a plan view and a side elevation, respectively, of the steam table showing a modification, and

Figures 6 and 7 are a plan view and side view, respectively, of the steam table showing another modification.

Gem duck is the name usually employed 55 in the shoe manufacturing industry for canvas duck which is coated on one side with an adhesive, generally a gutta percha compound. This duck is used particularly for reinforcing insoles, being applied to the insoles according to the well known "gem" or 60 "economy" systems of reinforcing. Duck, as supplied to the workmen in the shoe factory, comes in rolled strips, the strips being the proper width for application to an insole. In order to render the adhesive coating on the duck tacky, or soft, so it may be properly applied to the insole to be reinforced, the duck is heated. This is usually done in machines in which a roll of gem 65 duck is placed and through which the strip of gem duck is drawn and heated preparatory to passing to the machine which cuts off the duck and applies it to the insoles.

The gutta percha coating on the duck is 70 rendered most tacky when subjected to both heat and moisture, and may be more easily handled when preliminarily softened.

In the drawings I have illustrated my invention as embodied in a machine for moistening and heating the gem duck so as to 75 supply it in the best condition for application to the insoles.

Referring to the illustrated embodiment 80 of the invention, the machine consists of a table 2 supported on legs or standards 3. Supported beneath the table is a reel, or plurality of reels, 4 on which may be placed, as illustrated, one or more rolls 5 of gem duck, between which is located a separator 85 5' preventing one of the rolls from imparting movement to the other. As illustrated, the gem duck is in strips of the proper width to be supplied to the insole reinforcing machines. Supported on the legs 3 beneath the table is a water box 6 which is 90 maintained full of water. An immersing roller 7 directs the strips of gem duck 8 from the reels 4 beneath the surface of the water so that the material is saturated and 95 preliminarily softened to facilitate forming in, as described. The immersing roller 7 is 100

preferably mounted on links 9 so it may be readily swung up out of the tank to permit the insertion of duck beneath it. A stop 10 may be provided for preventing the roller 5 from swinging too far to the right, as viewed in Figure 1, and being drawn up out of the water by the pull on the strips of duck.

From the water box 6, the strips of duck 10 pass up over suitably separated guide rollers 15 onto the top of the table 2. The top of the table 2 comprises a steam forming or containing chest 16, supplied with a constant level of water by means of a water 15 reservoir 17 closed at the top and having its open lower end 18 positioned that the water level is maintained at the proper point. The steam chest may be heated by a gas 20 burner 19, or the like, beneath or adjacent thereto.

The top of the steam chest for a portion of its length is provided with a large number of perforations 20 through which the steam passes and is directed against the 25 strips 8 of preliminarily softened gem duck which are being drawn across the table, and drives to the surface and softens the adhesive so that the strips are ready for use. The gem duck, after thus being rendered 30 tacky by the moist heat, is drawn from the perforated portion of the table to the left onto the solid or imperforate heated portion 20', where it is maintained in proper softened and sticky condition for use. The 35 reel 4 is so placed that the duck travels around the rollers 7 and 15 with its sticky side outermost, and over the table 2 with its sticky side uppermost.

In this machine the duck is first thoroughly 40 saturated with water in the water box to soften the duck body, and then is given a prolonged exposure to moist heat as it is drawn over the perforate portion of the table 2, so that the adhesive coating is rendered as tacky as possible, and the strip 45 in the best condition for its application to the insoles.

In Figures 4 and 5 is illustrated a modification, in which the table instead of being 50 provided with a water feed to the steam chest 16, is supplied directly with steam. The steam preferably at about one pound pressure, is supplied to the steam chest 16 by a pipe 21, and the water of condensation 55 escapes through a drip pipe 22. The table is heated by the action of the steam and due to the provision of a large number of perforations in a portion of its upper surface, as before described, a portion thereof 60 escapes to moisten and heat the gem duck.

In Figures 6 and 7 is illustrated another modification in which water is supplied to the steam chest 16, but instead of having the steam chest heated by a gas flame, as in 65 Figure 1, it is heated electrically by means

of an electrical resistance pad 23 suitably placed at or adjacent the bottom of the chamber 16.

While I have specifically illustrated and described the preferred embodiment of my invention, it is to be understood that the invention is not limited to its illustrated embodiment, but may be otherwise embodied within the scope of the following claims.

I claim:

1. A machine for heating and moistening gem duck, comprising a reel for holding a roll of gem duck, a water box through which the gem duck is drawn, said box having means for immersing the gem duck therein, 80 and a perforated table supplied with steam and over which the gem duck is drawn, so as to be exposed to the softening action of the steam, substantially as described.

2. A machine for heating and moistening 85 gem duck, comprising means for subjecting the duck to the direct action of water, a perforated surface over which the gem duck is subsequently drawn, and means for supplying steam through the perforations to heat and moisten the duck, substantially as described.

3. A machine for heating and moistening 95 gem duck, comprising a water box through which the gem duck is first passed, and a perforated table on which the uncoated side only of the gem duck is afterward exposed to moist steam, substantially as described.

4. A machine for heating and moistening 100 gem duck, comprising means for subjecting the duck to the direct action of water, and a steam table over which the gem duck is subsequently drawn and exposed on its uncoated side only to moist steam, substantially as described.

5. The method of preparing gem duck for 110 application to insoles, which consists in preliminarily softening the same by one softening agent to facilitate the forming in thereof, subjecting the uncoated surface only of the duck so softened directly to the action of another softening agent in the form of moist steam to drive the adhesive to the surface and soften the same, and then maintaining the heated and softened duck in such 115 condition until ready for use, substantially as described.

6. The method of preparing gem duck for 120 application to insoles, which consists in softening the duck to facilitate the forming in thereof, and then subjecting the duck on its uncoated side only directly to the action of moist steam to drive the adhesive to the surface and soften the same, substantially as described.

7. A machine for heating and moistening 125 gem duck, comprising a table over which the gem duck is drawn, said table having a perforate end portion extending throughout a considerable portion of its length over which 130

the duck is first drawn, and an imperforate end portion extending throughout a considerable portion of its length over which the duck is subsequently drawn, and means for applying a heating and softening agent to said duck during its passage over said table, substantially as described.

8. The method of preparing gem duck for

application to insoles, which consists in drawing a strip of gem duck through water 10 to moisten it and afterward subjecting its uncoated side only to contact with moist steam, substantially as described.

In testimony whereof, I have hereunto set my hand.

FRANK C. FIX.
